REFRIGERATOR LATCH

George E. Curtiss, Jr., New Britain, Conn., assignor to The Stanley Works, New Britain, Conn., a corporation of Connecticut

Application May 28, 1940, Serial No. 337,639

5 Claims. (Cl. 292—223)

The present invention relates to latches of the type used on refrigerator doors, though not limited thereto, and is concerned with a novel retracting mechanism for withdrawing the latch bolt.

An object of the present invention is to provide an improved latching mechanism of simple, compact and inexpensive construction having a bolt normally effectively held in latching position by a heavy spring and a novel retracting mechanism including a manually operable handle located remotely from the latching mechanism and cooperably connected thereto for retracting the bolt.

A further object of the present invention is to provide a latching mechanism of this type having the further advantage of requiring the application of but slight effort to the manually operable handle for retracting the latch bolt to unlatched position.

A still further object of the invention is to provide a retracting mechanism having a handle so constructed and so journaled that it can be moved in a variety of directions to accomplish the desired retraction of the latch bolt.

Other objects will be in part obvious and in part pointed out more in detail hereinafter.

The invention accordingly consists in the features of construction, combination of elements and arrangement of parts which will be exemplified on the construction hereafter set forth and the scope of the application of which will be indicated in the appended claims.

In the accompanying drawings:

Figure 1 shows a front elevation of a portion of a door having mounted thereon latching and operating mechanism made in accordance with the present invention;

Fig. 2 shows the operating mechanism of Fig. 1 before mounting on the door with the handle and escutcheon removed therefrom;

Fig. 3 is a cross-sectional view of the operating mechanism taken through lines 3—3 of Fig. 1;

Fig. 4 is a cross sectional view taken along line 4—4 of Fig. 3 showing an end elevation of the latch operating mechanism;

Fig. 5 is an enlarged cross sectional view taken through line 5—5 of Fig. 1 showing the latch mechanism in latching position;

Fig. 6 is a view similar to Fig. 5 illustrating the latching mechanism in retracted position; and

Figs. 7 and 8 are side and rear elevations respectively of the latching mechanism illustrated

in Fig. 5 showing the mechanism in latching position.

In order to illustrate one application of the present invention there is shown generally a refrigerator door D to which there is secured a frame F for supporting a latching mechanism L including a latch bolt B', and a manually operable retracting mechanism B including a handle H. As indicated in Figs. 1, 2 and 7 the frame F includes a channel shaped section 10 having welded to its upper end a retracting mechanism support 12 and having similarly welded to its lower end a U shaped mounting 14 for the latch mechanism. In the present instance the support 12 is provided with a vertical bearing plate 16 having a vertical end wall 18 and upper and lower horizontal side walls 20 at right angles thereto and to the bearing plate 16. In order to properly secure the frame F to the door D the outer ends of the walls 18 and 20 are respectively provided with ears 22 and 24 securable to a mounting plate 26 on the refrigerator door D by means of suitable screws 28 and 30. The lower end of the frame, comprising the U shaped mounting 14 is similarly provided with flanges 32 securable to another mounting plate 34 on the door by means of rivets 36 as illustrated in Fig. 7.

Referring more specifically to the retracting mechanism B it includes a crosshead C slidably mounted on the support 12. To accomplish this, the crosshead comprises a rear stem portion 38 slidably secured in a slot 40 in the end wall 18; and a flat bearing surface 42, forwardly thereof, slidably secured to the bearing plate 16 by a headed stud 44, fixed to the plate 16, and extending through an elongated slot 46 in the crosshead. A spring 50 surrounds the stem 38 and is compressed between the end wall 18 and a pair of shoulders 52 on the stem whereby the crosshead C is normally urged to the left as indicated in Figs. 2 and 3. According to the invention, the crosshead C must be moved rearwardly against the action of the spring 50 to retract the latch bolt B. In order to so move the crosshead, it is provided with a crossarm 54 having shoulders 56 and 57 operatively engaged by a yoke 58 secured to the handle H.

More specifically the yoke 58 includes a pair of spaced camming offsets or flanges 60 and 61 disposed forwardly of the crossarm shoulders 56 and 57 and in engagement therewith, for camming the shoulders rearwardly against the action of the spring 50. The yoke further includes an arcuated journaling flange 62 engaging the periphery of the bearing plate stud 44 for fulcrum-

ing the yoke thereon. The yoke 58 is secured on one end of a stud 64, the other end of which is secured by a screw 66 in a cored recess 68 in the journaled end of the handle H. The handle further comprises the usual lever arm 70 having a grip member 72 on the outer end thereof.

According to the present invention the handle H is movable in a variety of directions to actuate the crosshead C to retract the latch bolt B. For this reason the journaled end of the handle H comprises a half-round or hemispherical bearing end 74 movably secured in a mating socket 76 provided in a mounting fixture or escutcheon 78 having a slot 80 therein through which the stud 64 extends. The escutcheon is secured to the surface of the door wall 26 by the screws 28 and 30 which also mount the support 12 thereon, as heretofore indicated.

The retracting mechanism thus far described operates in the following manner: Referring to Fig. 1, when the handle H is rotated in either a clockwise or a counterclockwise direction, the stud 64 rotates therewith and one or the other of the yoke flanges 60 or 61 cams the cooperating shoulder of the crossarm 54 rearwardly against the action of the spring 50. It will be noted that the arcuated journaling flanges 62 fulcrums the yoke on the bearing plate stud 44 so that the yoke stud 64 does not frictionally bind in the escutcheon slot 48. The movement of the crosshead, thus effected, is sufficient to retract the latch to unlatching position, as will be hereinafter described. The same movement of the crosshead is obtained by drawing the handle H away from the door in a plane vertical thereto instead of moving it in a plane parallel with the door. When the handle is drawn away from the door, the yoke stud 64 is moved transversely in the escutcheon slot 48 and both of the flanges 60 and 61 engage the co-operating shoulders 56 and 57 to cam the crosshead rearwardly.

In order to transfer the movement of the crosshead to the latching mechanism L to retract the latch bolt, there is provided a transfer linkage comprising a pair of connected bell cranks 83 and 84 respectively, pivotally mounted at the upper and lower ends of the channel section 10. As shown in Fig. 1, one arm 86 of the upper bell crank lever 82 is provided with a flange 87 operatively engaging the free end of the crosshead stem 38. The other lever arm 88 is provided with an eyelet in which one end of a rod 89 is secured, and the corresponding arm 90 of the lower bell crank 84 is provided with a similar eyelet in which the lower end of the rod 89 is secured. The remaining arm 92 of the crank 84 is provided with a flange 93, similar to flange 87, for operatively engaging the latch mechanism L as will be hereinafter described.

Referring more specifically to the latch mechanism L, as illustrated in Figs. 5 through 8, there is provided a latch bolt support 94 pivotally mounted on a pin 95 secured between the walls of the U shaped mounting 14. As depicted, the latch bolt support 94 comprises a pair of connected spaced flanges 96 between which the latch bolt B' is pivotally supported on a pin 97. Likewise, pivotally secured to the latch bolt B' on a pivot pin 98 is the forward end 99 of a plunger 100. A slot 101 is cut in the other end of the plunger for receiving a rearwardly disposed pin 102 secured between the flanges 96 of the support 94; the slot 101 being of such length as to limit longitudinal movement of the plunger. A heavy spring 103 surrounds the plunger and is

interposed between a shoulder 104 thereon and the pin 102 whereby the plunger and the bolt B' are urged to the forwardmost position permitted by the slot 101.

Likewise journaled on the pin 102 is one end of a toggle 108 normally retaining the latch bolt support 94 in the latching position illustrated in Fig. 5. The toggle 108 comprises the spaced links 109 (see Fig. 7) having secured therebetween a stud 110 pivotally supporting one end of the lever 111 which is, in turn, pivotally mounted at its center on the bearing shaft 112 secured between the walls of the U shaped mounting 14. The lower end 113 of the lever extends through a notch 114 in the frame F and the end 115 thereof constitutes a stop for limiting the clockwise rotation of the lever 111. There is further provided on the shaft 112 a spring 116 normally urging the lever into engagement with the stop 115 whereby the latch support 94 is normally held in latching position. Also engageable with the lower end 113 is the flange 93 of the bell crank lever 84, movement of which rotates the lever 111 counterclockwise against the action of the spring 116 to thereby break the toggle and retract the latch bolt as indicated in Fig. 6. As heretofore indicated, the desired movement of the bell crank lever 84 is obtained by actuating the handle H in either of the manners heretofore indicated. When thus retracted, the latch bolt B' and the support 94 are drawn to an unlatched position as a unit and without further compressing the heavy latch bolt spring 103. Due however, to the pivotal mounting of the latch bolt B' within the latch support 94, when the unit is in latching position the latch bolt B' may be forced rearwardly towards unlatched position to permit the closing of the refrigerator door. This occurs when a strike 107 located on the door jam D' engages the end of the bolt and cams it rearwardly against the spring 103 without breaking the toggle 108. When the strike has cleared the latch bolt, the spring 103 will urge the latch bolt into a keeper 108 formed integral with the strike.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a latch, a frame member, a bolt support pivotally mounted on the frame member for movement into and out of latching position, a latch bolt pivotally mounted in the support with the free end of the bolt projecting towards the pivotal mounting of the support, means normally urging the latch bolt to latching position and allowing pivotal movement of the bolt independently of movement of the support when the bolt is engaged by a strike, and means including toggle linkage for pivoting the support and bolt as a unit out of latching position.

2. In a latch, a frame member, a bolt support pivotally mounted on the frame member for movement into and out of latching position, a

latch bolt pivotally mounted in the support with the free end of the bolt projecting towards the pivotal mounting of the support, a toggle linkage normally retaining the support in latching position, spring means normally urging the latch bolt to latching position and allowing pivotal movement of the bolt independently of movement of the support when the bolt is engaged by a strike, and means for pivoting the support and bolt as a unit out of latching position.

3. In a latch, a frame member, a bolt support pivotally mounted on the frame member for movement into and out of latching position, a latch bolt pivotally mounted in the support with the free end of the bolt projecting towards the pivotal mounting of the support, means normally urging the latch bolt to latching position and allowing pivotal movement of the bolt independently of movement of the support when the bolt is engaged by a strike, toggle means normally holding the support in latching position, and means for actuating the toggle to pivot the support and bolt as a unit out of latching position.

4. In a latch, a frame member, a latch bolt support pivotally mounted on the frame member, a latch bolt pivotally mounted on the support with the free end of the bolt projecting toward the pivotal mounting of the support, a lost motion connection between the free end of the latch bolt and the support, said lost motion connection including a heavy spring normally urging the bolt to latching position relative to the

support to take up the lost motion between the latch bolt and the support, a toggle linkage between the support and the frame adapted in one position to hold the support in latching position relative to the frame, light spring means normally urging the toggle to said position, and means positioned remotely from the toggle and in operable engagement therewith for forcing the toggle to a second position to thereby retract the latch support to unlatched position.

5. In a latch structure including a frame mountable on a door, a latch bolt support pivotally mounted on the frame, a latch bolt pivotally mounted on the support, a plunger pivotally secured at one end to the latch bolt having a lost motion connection at its other end comprising an elongated slot slidably supported on a pin secured to the support, a heavy spring compressed between the pin and the bolt for urging the bolt to the forward position allowed by the lost motion connection, a toggle linkage between said pin and a shaft secured to the frame adapted in one position to hold the latch bolt support in latching position, light spring means normally urging the toggle linkage to said position, and retracting means including a handle positioned remotely from said toggle and operably connected thereto by a transfer linkage for forcing the toggle linkage to a second position and thereby retracting the latch bolt support and the latch bolt carried thereby to unlatched position.

GEORGE E. CURTISS, JR.
